INTERNAL COMBUSTION ENGINE

Jacobus Ludwich Wilhelm Weber,
Leens, NetherlandsApplication July 9, 1932, Serial No. 621,555
In the Netherlands July 10, 1931

9 Claims. (Cl. 123—50)

This invention relates to a two stroke cycle internal combustion engine with slide valve regulation in which the piston and the valve provided with admission and exhaust ports are rigidly connected to each other or constitute a single body, the side next to the crankshaft acting as the working piston and the other side acting as a pump or compressor.

The object of the invention is to secure in such a prime mover a more certain confinement of the gases contained and compressed in the combustion chamber. This result is secured according to the invention by disposing the head of the piston so that it extends obliquely towards the combustion chamber admission port arranged in the slide valve, said admission port in the upper dead centre position of the piston establishing communication through a by-pass passage between the combustion chamber and the pump chamber, while one or more piston rings provided on the slide valve are arranged between the admission port aforesaid and the admission port for the pump chamber which in the lower dead centre position of the slide valve cooperates with an inlet in the wall of the cylinder. Said piston ring or rings is or are accordingly located partially on both sides of the head of the piston and ensure a reliable sealing.

In the accompanying drawings, Fig. 1 is a diagrammatic section of an internal combustion engine according to the present invention with the parts in one dead centre position and Fig. 2 is a similar view with the parts in the reverse dead centre position. Figs. 3 and 4 are sections at right angles to one another of a second constructional example of the invention.

In Figs. 1 and 2, 1 is the engine cylinder with its head or cover 2. The end next to the crank-shaft is closed by a fixed head 3. The piston which works in the cylinder consists of a hollow cylinder 5 carrying externally piston rings and an oblique head 4. As is shown in the figures the external diameter of the fixed head 3 is substantially equal to the internal diameter of the cylinder 5, so that the latter fits into the space between the fixed head and the cylinder in sliding engagement with the adjacent side walls of these members. The fixed head 3 is also provided with piston rings.

In the head or cover 2 of the engine cylinder is situated a by-pass passage 6, communicating with a port 7 in the wall of the cylinder. The hollow cylinder 5 is provided with two longitudinally unaligned ports 8 and 9, of which the port 8 lies immediately above the head 4 of the piston in an

upwardly prolonged part of the slide valve, while the port 9 lies immediately below the head at the opposite side.

In consequence hereof, as the figures show, the port 9 is further away from the crankshaft than the port 8. The port 9 cooperates, in the upper dead centre position of the piston valve with the port 7. In the same position a port 10 in the piston valve cooperates with the exhaust port 11 in the engine cylinder 1. In the lower dead centre position of the piston the port 8 in the piston valve coincides with an admission port 12 in the engine cylinder.

The fixed head 3 has two oppositely situated slots 13 in it to clear a gudgeon connected to the piston valve 5. To this gudgeon is attached the connecting rod 15.

The piston valve is also provided below the slot 9 with an internal guide rib 16 which directs the entering gases along the inclined head 4 of the piston. At the level of this guide rib 16 piston rings are arranged on the outside of the piston valve which in the position shown in Fig. 1 that is at the end of the compression stroke and at the beginning of the expansion stroke, prevent the escape of gases through the valve port 9, the space between the valve and the wall of the cylinder, the admission port 12 and the exhaust port 11. As it is desirable for an effective and permanent sealing that the temperature of the piston rings shall remain within certain limits, it is advisable to make the guide rib 16 hollow, whereby the wall of the piston valve at the level of the piston rings is protected from the direct action of the temperatures prevailing in the cylinder.

In an internal combustion prime mover with a vaporizer there is placed in the cylinder wall at the level of the combustion chamber admission port 9 a spark plug 17 which in the position shown in Fig. 1 ignites the compressed gaseous mixture. In this position and during the last part of the downward and the first part of the upward stroke of the piston a fresh gaseous mixture enters the cylinder 1 above the head of the piston. During the working stroke of the piston this gaseous mixture is compressed until in the position shown in Fig. 2 relief of the pressure takes place through the passage 6 and the port 7. On the downward stroke the waste gases are first expelled through the exhaust ports 10 and 11 by the fresh gaseous mixture entering through 6, 7 and 9 which is then compressed after the port 11 has been cut off by the valve. By the directing action of the guide rib 16 the entering gaseous mixture flows along the head of the pis-

ton, so that the waste gases are completely expelled.

The constructional example of the invention shown in Figs. 3 and 4 differs in the main from 5 the constructional example shown in Figs. 1 and 2 only by the fact that the number of ports and slots is doubled, the base of the piston being therefore also altered to correspond. Thus the engine has two oppositely arranged slots 7 in the 10 cylinder 1, two ports 9 in the piston valve underneath the head 4 of the piston to cooperate with the ports 7, two ports 8 in the valve above the base 4, two oppositely situated admission ports 12 in the cylinder 1 and two oppositely situated exhaust ports 11 likewise in the cylinder 1, the admission and exhaust ports being angularly displaced by 90°. In like manner the piston has two ports 10 and the engine cylinder two ignition ports 17. In this case also the head of the piston 15 runs obliquely, so that the admission ports 8 lie immediately over the lower end and the ports 9 immediately below the upper end of the head 4 of the piston. Owing to the duplicating of the ports 8 and 9 and their position with respect to 20 each other the head of the piston in this case assumes the form of a transverse member extending from one side thereof to the other as shown in Fig. 3. The action is the same as that of the constructional form shown in Figs. 1 and 2. 25 When the present invention is applied to a Diesel engine, fresh air enters through the admission ports 12 and 8 respectively. The sparking plug 17 will be replaced in this case by a nozzle for spraying in the fuel.

30 35 What I claim is:—

1. In a valveless two-cycle internal combustion engine, in combination, a cylinder having spaced communicating openings adjacent to the head end thereof and forming a by-pass, a fixed head disposed concentrically with the crank end of said cylinder, a piston slidably disposed between and contacting with the inner and outer peripheries of the cylinder and the fixed head respectively, a space between the head of the piston and the head of the cylinder, and a space between the head of the piston and the fixed head, said spaces forming a pump chamber and a combustion chamber respectively, the head of the piston being inclined to the longitudinal axis of the system, the wall of the piston extending beyond said piston head and into the pump chamber, an inlet port arranged in said piston extension immediately above the lower part of the piston head, a fuel inlet port for the pump chamber in the cylinder wall, said piston inlet port communicating on the full instroke of the piston with said cylinder inlet port, a spark plug opening in said cylinder wall, a second piston inlet port immediately beneath the higher part of the piston head, said second piston inlet port communicating on the full outstroke of the piston with the pump chamber through the by-pass and on the full instroke of the piston with said spark plug opening, an exhaust port in said cylinder, an exhaust port in the piston arranged to align with said exhaust port in the cylinder on the full outstroke of the piston, and sealing means on said piston between said first and second piston inlet ports, said sealing means located partially on both sides of the head of the piston.

2. In a valveless two-cycle internal combustion engine, in combination, a cylinder having spaced communicating openings adjacent to the head end thereof and forming a by-pass, a fixed head

disposed concentrically with the crank end of said cylinder, a piston slidably disposed between and contacting with the inner and outer peripheries of the cylinder and the fixed head respectively, a space between the head of the piston and the head of the cylinder, and a space between the head of the piston and the fixed head, said spaces forming a pump chamber and a combustion chamber respectively, the head of the piston being inclined to the longitudinal axis of the system, the wall of the piston extending beyond said piston head and into the pump chamber, an inlet port arranged in said piston extension immediately above the lower part of the piston head, a fuel inlet port for the pump chamber in the cylinder wall, said piston inlet port communicating on the full instroke of the piston with said cylinder inlet port, a spark plug opening in said cylinder wall, a second piston inlet port immediately beneath the higher part of the piston head, said second piston inlet port communicating on the full outstroke of the piston with the pump chamber through the by-pass and on the full instroke of the piston with said spark plug opening, an exhaust port in said cylinder, an exhaust port in the piston arranged to align with said exhaust port in the cylinder on the full outstroke of the piston, sealing means on said piston between said first and second piston inlet ports, said sealing means located partially on both sides of the head of the piston, and a guide rib for the combustible gas, said guide rib arranged within said piston adjacent and below said second piston inlet port and extending over a portion of the circumference of the piston.

3. In a valveless two-cycle internal combustion engine according to claim 2, characteristic in that the guide rib for the mixture of gas is hollow and in that the sealing means are located on said piston at the level of said guide rib.

4. In a valveless two-cycle internal combustion engine, in combination, a cylinder having spaced communicating openings adjacent to the head end thereof, said spaced communicating openings forming two by-passes, a fixed head disposed concentrically within the crank end of said cylinder, a piston slidably disposed between and contacting with the inner and outer peripheries of the cylinder and the fixed head respectively, a space between the head of the piston and the head of the cylinder and a space between the head of the piston and the fixed head forming a pump chamber and a combustion chamber respectively, the head of the piston being provided with a transverse prolongation adjacent the center thereof, the wall of the piston extending beyond said piston head and into the pump chamber, a pair of diametrically opposed inlet ports arranged in said piston extension immediately above the lower part of the piston head, a pair of diametrically opposed inlet ports for the pump chamber in the cylinder wall, said piston inlet ports communicating on the full instroke of the piston with the said cylinder inlet ports, a pair of opposed spark plug openings in said cylinder wall, a second pair of piston inlet ports immediately beneath the higher part of the piston head, said second pair of piston inlet ports communicating on the full outstroke of the piston with the pump chamber through the by-passes and on the full instroke of the piston with the spark plug openings in the cylinder wall, a pair of exhaust ports in said cylinder, a pair of exhaust ports in said piston arranged to align with said cylinder exhaust ports on the full outstroke of the piston,

and sealing means on said piston between said first and second pairs of piston inlet ports, said sealing means located partially on both sides of the head of the piston.

5. A piston for a valveless two-cycle internal combustion engine, said piston comprising a hollow cylinder, said cylinder being open at one end, a head for said piston at the other end of said cylinder, said head being inclined to the longitudinal axis of said cylinder, the wall of said cylinder extending beyond said head, an inlet port in said piston extension immediately above the lower part of the head, a second inlet port in the main body of said piston arranged immediately beneath the higher part of the piston head, an exhaust port in said piston adjacent the open end thereof, and sealing means on said piston arranged circumferentially thereof, said sealing means located longitudinally of said piston between said first and second inlet ports.

6. A piston for a valveless two-cycle internal combustion engine, said piston comprising a hollow cylinder, said cylinder being open at one end, a head for said piston at the other end of said cylinder, said head being inclined to the longitudinal axis of said cylinder, the wall of said cylinder extending beyond said head, an inlet port in said piston extension immediately above the lower part of the head, a second inlet port in the main body of said piston arranged immediately beneath the higher part of the piston head, an exhaust port in said piston adjacent the open end thereof, sealing means on said piston arranged circumferentially thereof, said sealing means located longitudinally of said piston between said first and second inlet ports, and a guide rib arranged on the inner wall of said piston below and adjacent said second inlet port, said guide rib extending over a portion of the inner circumference of said piston.

7. A piston for a valveless two-cycle internal combustion engine, said piston comprising a hollow cylinder, said cylinder being open at one end, a head for said piston at the other end of said cylinder, said head being inclined to the longitudinal axis of said cylinder, the wall of said cylinder extending beyond said head, an inlet port in said piston extension immediately above the lower part of the head, a second inlet port in the main body of said piston arranged immediately beneath the higher part of the piston head, an exhaust port in said piston adjacent the open end thereof, sealing means on said piston arranged circumferentially thereof, said sealing means located longitudinally of said piston be-

tween said first and second inlet ports, and a guide rib arranged on the inner wall of said piston below and adjacent said second inlet port, said guide rib extending over a portion of the inner circumference of said piston, said guide rib being hollow, said guide rib and said sealing means arranged opposite each other longitudinally of said piston.

8. In a valveless two cycle internal combustion engine, in combination, a cylinder having spaced communicating openings adjacent to the head end thereof and forming a by-pass, a fixed head disposed concentrically with the crank end thereof, a piston slidably disposed between the inner and outer peripheries of the cylinder and the fixed head, forming with the cylinder head and the fixed head a compression chamber and a combustion chamber, respectively, the head of the piston being joined to the vertical wall thereof intermediate its length and at one point at a lower horizontal level than at another point, the wall of the cylinder having a spark plug opening, the piston wall having an inlet port below and adjacent to the higher point at which the piston head is joined to the piston wall, said inlet port communicating on the full upstroke of the piston with the compression chamber through the by-pass and on the full downstroke of the piston with said spark plug opening, the piston wall having a second inlet port located above the lower point at which the piston head is joined to the piston wall and below the level of said first inlet port, the cylinder wall having a fuel inlet port for said compression chamber arranged to communicate with said second piston inlet port on the full downstroke of the piston, said piston wall having an exhaust port, said cylinder having an exhaust port arranged to align with the exhaust port in the piston wall on the full upstroke of the piston, and sealing means located on said piston above the first piston inlet port and between the levels of the first and second inlet ports.

9. A piston for a sleeve valve two-cycle internal combustion engine comprising a skirt portion and a piston head extending across said skirt intermediate the length thereof, said skirt having a port in a portion thereof, said head having a prolonged portion establishing communication between the inside of said piston and said port, and said skirt having a second port disposed above said head and below the level of said first-mentioned port, and sealing means on said piston, said sealing means being arranged circumferentially of said piston between said ports.

JACOBUS LUDWICH WILHELM WEBER. 55
